Primary Examiner — David Muller*Assistant Examiner* — Nathan Johnston(74) *Attorney, Agent, or Firm* — Greer, Burns & Crain, Ltd.(57) **CLAIM**

The ornamental design for a floor register grille, as shown and described.

DESCRIPTION

FIG. 1 is a top perspective view of the floor register grille showing my new design;

FIG. 2 is a top plan view thereof;

FIG. 3 is a front elevation view thereof, the rear elevation view being identical;

FIG. 4 is a side elevation view thereof, both sides being identical;

FIG. 5 is a top perspective view of a second embodiment of the floor register grille;

FIG. 6 is a top plan view thereof;

FIG. 7 is a front elevation view thereof, the rear elevation view being identical; and,

FIG. 8 is a side elevation view thereof, both sides being identical.

1 Claim, 4 Drawing Sheets(56)
